UNITED STATES PATENT OFFICE.

HOWARD E. CADE, OF PENCOYD, AND DAVID R. KNAPP, OF PHILADELPHIA, PENNSYLVANIA

BOILER-FEED REGULATOR.

No. 891,981.

Specification of Letters Patent.

Patented June 30, 1908.

Application filed February 26, 1908. Serial No. 417,897.

To all whom it may concern:

Be it known that we, HOWARD E. CADE and DAVID R. KNAPP, citizens of the United States, residing, respectively, at Pencoyd, in the county of Montgomery, and at Philadelphia, in the county of Philadelphia, both in the State of Pennsylvania, have invented certain new and useful Improvements in Boiler-Feed Regulators, whereof the following is a specification, reference being had to the accompanying drawing, and forming part of the specification.

Our invention relates to that class of devices wherein an expansion tube is connected to a boiler at the mean water level and so arranged that when the water in the boiler is at its normal height, the expansion tube is closed to the steam space of the boiler by the water in the boiler acting as a seal to the steam to the expansion tube and vice versa, when the water in the boiler is below normal, due to the evaporation of the water, the expansion tube is connected to the steam space in the boiler, the difference in temperature of the expansion tube when open and closed to the boiler steam being utilized to expand and contract the expansion tube.

It is the object of our invention to provide simple and efficient means for automatically regulating the flow of water to a boiler and to this end our invention comprises devices in coöperative relation with the said expansion tube whereby a valve on the boiler feed line is opened upon the expansion of said tube and closed upon the contraction of said tube, also means for the prevention of buckling of said tube upon the expansion and contraction of same.

In the accompanying drawing, Figure 1 is an elevation of a boiler, showing our invention applied thereto. Fig. 2 is a plan showing the arrangement of an adjustment bar, and a bell crank lever to permit the adjustment of the parts.

In Fig. 1, 16 is a boiler provided with a feed water pipe 17 having interposed in same a valve 18 for the control of the water to the boiler.

1 is an expansion tube connected by means of pipe 11 to a gage glass 14 at the mean water level.

12 is a pipe leading from the top of the gage glass to the steam space of the boiler, so that when the water in the boiler falls below the mean level, steam is admitted to the expansion tube by pipe 12, gage glass 14 and

11, also when the water in the boiler is at the mean level, the expansion tube is closed to steam from the boiler by the water in the gage glass being slightly above the opening to the pipe 11 and consequently acting as a seal to the pipe 11 and 12.

13 is a pipe for draining the water of condensation in the expansion tube 1 back to the boiler and is connected to the boiler below the water level.

In practice pipes 11 and 13 are small in comparison with the expansion tube 1 and are put in place after expansion tube 1 has been connected and adjusted throughout. The maximum travel of the expansion tube is a small fraction of an inch and the length of pipes 11 and 13 and the number of bends required to make the said connections enables these pipes to have sufficient flexibility to allow the expansion tube 1 to expand and contract and perform its function. One end of the expansion tube is rigidly connected to the part 32 which is pivoted on the adjustable support 10 mounted on the base 35. The other end of the expansion tube is free to move and is connected to the part 9 which is connected to the arm 33 of the bell crank lever 3.

4 is a support pivoted to a rigid block 7 mounted on the base 35 and has mounted on it the part 5 upon which is pivoted the bell crank lever 3 by means of the spindle 26.

2 is an adjustable rod, one end of which is rigidly connected to the part 34 which is pivoted by the spindle 26 on the part 5 of the support 4. The bell crank lever 3 being also pivoted on the spindle 26 as shown in Fig. 2. The other end of the rod 2 extends through the support 10 and is threaded and provided with the nut 30. By moving the nut 30 along the threaded end of the adjustable rod 2 and as the standard 4 is pivoted to the block 7 an adjustment of the relation of the parts is effected. The arm 6 of the bell crank lever 3 is connected by the link 24 to the arm 22 of the toggle lever 39, the other arm 38 of the toggle lever being pivotally connected with the crosshead 20 by the link 37 and the spindles 28 and 29. A valve stem 21 of the check valve 18 is rigidly connected to the crosshead 20, the check valve 18 controlling the flow of feed water from the pipe 17 to the boiler 16.

19 are guides upon which the cross head 110 is free to move.

25 is a stop carried by the guide 19 which

serves to limit the travel of the toggle levers or the crosshead. The lever arm 22 of the toggle lever 39 is provided with a weight 23 and is adjustably secured thereon by a set screw or other suitable device, its function being to balance or partially balance the pressure in the pipe 17.

The parts as shown are such as they occupy when the water is low and the valve 18 is opened on the feed line and the action of the apparatus is as follows, the adjustment of the parts by the nut 30 on the rod 2 being effected. The water being low and the water seal being broken on the pipe 11 at the water gage 14, steam has entered the expansion tube and caused it to expand due to the increased temperature of the tube caused by the temperature of the steam. The expansion of the tube moved the lever arm 33 of the bell crank lever 3 clockwise around the spindle 26 thereby uplifting the arm 6 of the bell crank lever 3. The uplifting of the arm 6 of the bell crank lever raised the arm 22 of the toggle lever 39 through the link 24, thereby moving arm 38 of the toggle lever 39 clockwise around the spindle 27 and raised the crosshead 20 and valve spindle 21 through the link 37. The raising of the valve spindle 21 opened the valve 18 to the boiler 16 and allows water to be admitted to the boiler. The water thus admitted will continue to rise in the boiler until the opening of pipe 11 to the gage glass 14 is closed to the steam space of the boiler 16 through the pipe 12 by the rise of water in the gage glass 14 and thus cutting off steam to the expansion tube. The expansion tube being cut off from steam has its temperature decreased causing it to contract and reversing the movement of parts of the expansion tube and thereby lowering the crosshead 20 and valve spindle 21 and closing the valve 18 to the admission of water to the boiler. The cross head as stated will lower until the link 38 engages the stop 25 which prevents any further downward movement. It is necessary to make provisions for counteracting the tendency of the expansion tube to buckle upon its expansion and contraction as would happen if the expansion tube 1 was not adjustably fixed to the support 10.

35 being a base located above the boiler is usually of rough surface due to dirt and paint and it is obvious that if the angle 55 formed by base 35 and the expansion tube 1 is fixed and cannot be varied considerable trouble will then be experienced in making the connection of part 9 to the lever arm 33 of the bell crank 3. If these connections do 60 not coincide upon the tightening down of the holding down bolts for the parts 7 and 10 an undue strain will be placed on the expansion tube 1 and cause it to buckle, and thereby affect its function upon expansion 65 by further buckling. In order to overcome

this objection a pivot connection is made between the expansion tube 1 and the support 10 which allows a limited change in the angle formed by the base 35 and expansion tube 1 and consequently a limited vertical adjustment of expansion tube 1 can be obtained when the support 10 is securely fixed to the base 35. It is obvious that with this adjustment the base of supports 7 and 10 need not lie in the same plane, which is desirable in case very uneven base locations are encountered or structural work does not permit.

Having thus described the nature and objects of our said invention, what we claim as new and desire to secure by Letters Patent, is:

1. In a boiler feed regulator of the character described in combination with a steam boiler and a water gage for same and an expansion tube over the level of said boiler and a feed water pipe for said boiler and a valve in said water pipe and toggle levers arranged to operate said valve and means operatively connecting said expansion tube to said levers, a stop limiting the travel of said toggle levers, a pipe connection from a predetermined water level of said gage to said tube, a drain from said tube leading to the water in said boiler, substantially as described.

2. In a boiler feed regulator of the character described in combination with a steam boiler and a water gage for same and an expansion tube over the level of said boiler and a feed water pipe for said boiler and a valve in said pipe and a reciprocating cross head attached to the stem of said valve and levers adapted to reciprocate said cross head and a means operatively connecting said expansion tube with said levers, a stop limiting the travel of said cross head, a pipe connection from a predetermined water level of said gage to said tube, a drain from said tube leading to the water in said boiler, substantially as described.

3. In a boiler feed regulator of the character described in combination with a steam boiler and a water gage for said boiler and an expansion tube over the level of said boiler and a feed water pipe to said boiler and a valve in said water pipe, and toggle levers connected at one extremity with the stem of said valve and an adjustable weight on the other extremity of said toggle levers, and a means operatively connecting said expansion tube with said levers, a stop limiting the travel of said toggle levers, a pipe connection from a predetermined water level of said gage to said tube, and a drain for said tube leading to the water in said boiler, substantially as described.

4. In a boiler feed regulator of the character described in combination with a steam boiler and a water gage for same and an

expansion tube over the level of said boiler and a feed water pipe for said boiler and a valve in said water pipe and toggle levers arranged to operate said valve and a means operatively connecting said expansion tube to said levers and a support for one end of said tube, a pivotal support for the other end of said tube, a stop limiting the travel of said toggle levers, a pipe connection from a predetermined water level of said gage and a drain from said tube leading to the water in said boiler, substantially as described.

5. In a boiler feed regulator of the character described in combination with a steam boiler and a water gage for same and an expansion tube over the level of said boiler and a feed water pipe for said boiler and a valve in said water pipe and a reciprocating cross head attached to the stem of said valve and levers adapted to reciprocate said cross head and a means operatively connecting said expansion tube with said levers and a support for one end of said tube, a stop limiting the travel of said cross head, a pivotal support for the other end of said tube, a pipe connection from a predetermined water level of said gage to said tube, and a drain from said tube leading to the water in said boiler, substantially as described.

30. 6. In a boiler feed regulator of the character described in combination with a steam boiler and an expansion tube over the level of said boiler and a support for one end of said tube and a lever connected with the free end of said tube and a valve in operative relation with said lever and a support for the fulcrum of said lever and a means provided for automatically admitting and cutting off steam to said tube, the first mentioned support pivotally connected to said expansion tube, substantially as described.

7. In a boiler feed regulator of the character described in combination with a steam boiler and a water gage for same and an expansion tube and a lever connecting one end of said tube and a support for the other end and a valve in operative relation with said lever and a support for the fulcrum of said lever and an adjustable rod connecting said supports, said support for the fulcrum of said lever pivotally connected at its base and the other said support pivotally connected to said expansion tube, said expansion tube located above the water level of said boiler, a pipe connection from a predetermined water level of said gage to said tube and a drain from said tube leading to the water in said boiler, substantially as described.

8. In a boiler feed regulator of the char-

acter described in combination with a steam boiler and a water gage for same and an expansion tube and a feed water pipe for said boiler and a valve in said water pipe and a toggle lever arranged to operate said valve and a means operatively connecting said expansion tube to said levers, a pivotal support for each end of said tube, an adjustable rod connecting same, a stop limiting the travel of said toggle levers, said tube located above the water level of said boiler, a pipe connection from a predetermined water level of said gage to said tube and a drain from said tube leading to the water in said boiler, substantially as described.

9. In a boiler feed regulator of the character described in combination with a steam boiler and a water gage for same and an expansion tube and a feed water pipe for said boiler and a valve in said water pipe and a reciprocating cross head attached to the stem of said valve and levers adapted to reciprocate said cross head and a means operatively connecting said expansion tube with said levers, a pivotal support for each end of said expansion tube, a stop limiting the travel of said cross head, said expansion tube located above the water level of said boiler a pipe connection from a predetermined water level of said gage to said tube and a drain leading from said tube to the water in said boiler, substantially as described.

10. In a boiler feed regulator of the character described in combination with a steam boiler and a water gage for same and an expansion tube and a feed water pipe to said boiler and a valve in said water pipe and toggle levers connected at one extremity with the stem of said valve and an adjustable weight on the other extremity of said toggle levers and a means operatively connecting said expansion tube with said toggle levers, a pivotal support for each end of said tube, a stop limiting the travel of said toggle levers, said expansion tube located above the water level of said boiler, a pipe connection from a predetermined water level of said gage to said tube and a drain from said tube leading to the water in said boiler, substantially as described.

In testimony whereof we have signed our respective names to this specification in the presence of two subscribing witnesses.
